UNITED STATES PATENT OFFICE.

ERIC C. MOORE, OF ROCHESTER, NEW YORK.

LOOSE-LEAF BINDER.

1,403,616.

Specification of Letters Patent. Patented Jan. 17, 1922.

Application filed February 28, 1918. Serial No. 219,615.

To all whom it may concern:

Be it known that I, ERIC C. MOORE, of Rochester, in the county of Monroe and State of New York, have invented certain new and useful Improvements in Loose-Leaf Binders; and I do hereby declare the following to be a full, clear, and exact description of the same, reference being had to the accompanying drawings, forming a part of this specification, and to the reference-numerals marked thereon.

My present invention relates to stationery and more particularly to loose leaf ledgers or binders and it has for its object to provide an improved device of this character in which all of the sheets or leaves may be locked or unlocked quickly and with a simple movement. Other objects of the invention are to enable the same locking means to be used for offsetting selected sheets from the others when desired and to provide means for holding the binder members separated while the leaves are being applied or removed. The invention also contemplates the use of a novel sheet or leaf in the binder. To these and other ends the invention resides in certain improvements and combinations of parts all as will be hereinafter more fully described, the novel features being pointed out in the claims at the end of the specification.

In the drawings:

Figure 1 is a transverse sectional and fragmentary view through a binder constructed in accordance with and illustrating one embodiment of my invention;

Figure 2 is a fragmentary longitudinal section in the general plane of the leaf retaining posts;

Figure 3 is a fragmentary plan view partly in section of one of the binding elements with the cover of its casing removed;

Figure 4 is a bottom plan view of the other element with part of the overlying mechanism removed;

Figure 5 is an enlarged transverse section taken on the line 5—5 of Figure 2 and looking in the direction of the arrow;

Figure 6 is an enlarged transverse section through the binding elements taken on the line 6—6 of Figures 3 and 4;

Figure 7 is a longitudinal sectional view through the binder similar to Figure 2 but showing a complete device and with the parts moved to different positions;

Figure 8 is a view similar to Figure 3 but with the parts in other positions;

Figure 9 is a fragmentary view of one of the binder leaves;

Figure 10 is a longitudinal sectional view in the plane of the posts through another embodiment of the invention;

Figure 11 is a plan view partly broken away and partly in section of one of the binding members of Figure 10 with the top of its casing removed;

Figure 12 is a sectional view through the posts but showing the rest of the binder in top plan view, parts being broken away, to illustrate the manner in which the leaves are locked in the embodiment of Figures 10 and 11;

Figures 13 and 14 are substantially diagrammatic views showing the manner in which selected leaves are offset in the binder; and

Fig. 15 is a detail section on line 15—15 of Figure 10.

Similar reference numerals throughout the several views indicate the same parts.

Referring first to the embodiment of the invention illustrated in Figures 1 to 9, the binder comprises two binding or compression elements indicated generally at A and B between which the leaves are compressed in the usual general relationship and while these binder elements are movable toward and from each other to clamp or release the leaves, I shall refer to the element A as the base member and to element B as the clamping element. The two covers of the binder 1 are hinged at 2 to the respective members and are shown in full and dotted line positions in Figure 1 to illustrate their relationship when the binder or ledger is closed and when it is open, respectively.

The base member A embodies a sheet metal casing composed of overlapping upper and lower channels 3 and 4 joined at the ends by cast plugs 5. Riveted or otherwise suitably secured in the lower portion 4, as shown in Figure 7, are a pair of inner fixed posts 6 that project from the top of the base sufficiently to provide a binder of desired capacity. Enclosed within the base casing just beneath the top 3 are a pair of sliding plates 7 guided in grooves or ways 8^a (Figures 4 and 7) in the castings 5. As the mechanism about to be described is duplicated at the two ends of the base, it will be described

in the singular as applying to either unit. Secured to the plates 7 is a post 8 which is one of a pair of outer movable posts that may be operated toward and from the posts 6 and that moves in a slot 9 in the top 3 of the base casing. The plate 7 is itself provided with a slot 10 to accommodate the adjacent fixed post 6 and is connected by a link 11 to a crank disc 12 having bearings 5 formed by the sides of the casing member 3 and by ears 13 struck down from the material of the latter. In the present instance, the link is pivoted to the respective parts by having its ends bent up at 14 to engage apertures 15 and 16 therein. A plate 17 supported on lugs 18 (Figure 6) struck from the channel 3 holds the parts assembled. A key 19 having a flattened face 20 fits an irregular opening in the center of the disc or crank plate 12 and serves as an operating member to actuate the slides 7 and carry the outer movable posts 8 toward and from the inner pair of fixed plates 6 between the locked position of Figures 7 and 8 and the unlocked position of Figures 2, 3 and 4. One of the links 11 may have an extension 21 that will interlock with a slot 22 in the end of the key when the posts are unlocked to prevent the key from being withdrawn while 30 the binder is in that condition for a purpose that will hereinafter appear.

The clamping member B is also formed of two overlapping channels 23 and 24 plugged at the ends by castings 25 and constituting a casing. Within the casing are confined friction clutch plates 26 that tilt on fulcrums formed by ears 27 thereon seated in apertures 28 in the lower channel member 23 and which clutch plates surround and are normally held locked against the fixed post 6 to prevent the clamping member B from moving away from the base member A by the ends of a leaf spring 29. This leaf spring has lugs 30 seated in notches in the channel member 23 in which notches it is held by inturned lugs 31 on the sides of the channel. Sliding plates 32 disposed against the bottom of the channel member 23 and guided in grooves 33 in the castings 25 have openings 34 to give clearance for the clutches 26 and adjacent cam flanges 35 which, when the plates are moved outwardly or in opposite directions, engage under the free ends of the clutches 26 and force them to inoperative position against the tension of the spring arms 29, allowing the posts 6 to slide freely through the clamping member B. Continued outward movement of the plates causes clamps or locking levers 36 thereon 60 rounding the movable posts 8 to grip the latter and thus hold the clamping member B from moving toward the base member A. This results from arms 37 on the locking levers 36 engaging with cams 38 on extensions of the castings 25.

The sliding plates 32, like the plates 7, constitute actuating mechanism for separating and for drawing together the movable posts 8 which pass through these plates 32 and the two sets of plates on the members A and B 70 act simultaneously under the operation of the same key 19. This key passes through the clamping member B and spring plate 29 and through a crank disc 39 similar to the crank disc 12 and supported in the same 75 manner by ears 40 and plate 41. It is also similarly connected to the plates 32 by links 42. When the key 19 is turned in one direction, therefore, both mechanisms operate to move the posts 8 from the leaf retaining position of Figures 7 and 8 to the inoperative position of Figures 2 and 3, the clutches 26 being released to permit the clamping member B to be drawn out on the posts and release ledger leaves held between the members A and B. A further movement of the key locks clamping member B on the posts 8, preventing it from slipping down toward the base member A. Movement of the key in the opposite direction draws the posts 8 together or toward the fixed post 6; releases the lock 36 so that the clamping member B may be forced down to pinch the leaves between it and the base member A, and releases the clutch 26 in each instance so that it will automatically 95 engage and prevent retrograde movement on the part of the clamping member. This locks the leaves in the binder both by compression and otherwise, due to the particular conformation of the leaves themselves. 100

The binding margin of one of the leaves is shown in Figure 9. It has a center slot 43 to accommodate the key 19 and on each side thereof a slot 44 at right angles to the edge 45 of the leaf to receive the fixed posts 6. Beyond these slots 44 are two elbow slots 46 which, in the instance shown, open both laterally and longitudinally of the leaf and binder members providing a locking portion 47. Therefore, when the movable posts 110 8 are spread, the sheet or leaf may be inserted in its true position between the binding members A and B, being centered on the fixed posts 6 through the medium of the slots 44. When thereafter the posts 8 are drawn 115 together again, they occupy the inner ends of the elbow slots 46 behind the locking portions 47 of the leaf and prevent its removal. In this way, the sheets may be inserted individually and successively and then all 120 locked securely together and in register by a single movement of the key 19.

The locking device 20 in the base member A for the key 19, as previously described, is operative only when the posts 8 have been 125 spread to release the leaves and permit the members A and B to be separated and it prevents the withdrawal of the clamping member B from pulling the key out of position.

In the embodiment of the invention shown 130

in Figures 10 to 15 inclusive, the formation of the binding members A and B is approximately the same but the movable posts 8^a constitute the inner pair and the fixed 5 posts 6^a constitute the outer pair. The mechanism in the clamping member B for actuating the posts comprises plates 32^a and 33^a having slots 48 in their approximate overlapping ends guided on a pivot stud 49. 10 Ears 50 struck out from the plate 33^a in forming a slot 51 for the key 19^a provide bearings on the plate for an eccentric 52. This eccentric also has a collar 53 defining its moving center that has a bearing in a 15 collar 54 in the channel member 23^a of the casing and the collar 53 is formed to receive the key 19^a and is irregular to lock against its flat face 20^a. This eccentric provides means for moving the plate 33^a in two 20 directions and opposite movement is communicated to the plate 32^a through a lever 55 pivoted on the stud 49. An arm 56 of this lever bears in a notch 57 in the plate 33^a on one side of the pivotal center and an arm 58 25 thereon bears in a notch 59 in the plate 32^a on the opposite side of the pivotal center.

Clutches 26^a cooperate with the fixed outer posts 6^a under the influence of individual leaf springs 27^a. These clutches tilt on lugs 30 60 on the channel member and are held in position by other lugs 61. Cam flanges 35^a on the plates 32^a and 33^a unseat the clutches when the posts 8^a are separated and the clamping levers 36^a that surround and 35 operate with the posts 8^a and are pivoted at 62 thereafter become operative by reason of arms 37^a thereon engaging pins or abutments 38^a fixed in the channel member 23^a. The action of the mechanism in the clamp- 40 ing member B of this embodiment is therefore substantially the same. The movable posts 8^a extend through the plates 32^a and 33^a and are actuated by them.

The mechanism in the base member A in 45 this second embodiment of the invention for actuating the movable posts 8^a is substantially the same as that employed in the clamping member B of the same embodiment and has therefore been shown only in section and 50 does not require extended description. The sliding plate to which the posts 8^a are riveted are indicated at 7^a; the eccentric at 52^a; the double lever arm at 55^a, and its pivot stud at 49^a. The fixed posts 6^a are secured to the 55 bottom channel member 4^a of the base as before, but at end positions instead of intermediate positions, as previously explained.

The leaf blanks used in this embodiment 60 are shown in Figures 13 and 14 in locked and unlocked positions, respectively. In each instance, the leaf marked C is normal and the one marked D is offset. Each leaf has a center slot 43^a to accommodate the key 19^a in the form of a double elbow having the

portions 43^b extending therefrom longitudinally of the sheet. On each side of it is a pair of elbow slots 44^a and 46^a opening transversely to the edge of the sheet and in which the longitudinally extending portions of each pair extend toward the center and 70 toward those of the other pair, locking shoulders 47^a, 47^b, 47^c, 47^d, 47^e, and 47^f being provided in each instance, there being two, 47^c and 47^d, on the center slot 43^a. When this leaf is inserted in the unlocked binder, 75 as in Figure 14, it is centered by the engagement of the various posts with the oppositely disposed straight walls of the slots and as the movable posts 8^a are drawn together, they lock behind the shoulders 47^b 80 and 47^e, as shown in Figure 13, the sheet C in this case being in normal position. If it is desired to offset the sheet, as at D, toward the top of the binder, the lower fixed post 6^a becomes idle and the upper slot 44^a becomes 85 idle. One of the movable inner posts 8^a locks behind the locking shoulder 47^f of the sheet and the other one behind the locking shoulder 47^d of the key slot 43^a, the key being accommodated in the upper one of the 90 lower pair of slots 46^a. The posts therefore lock in the same manner in either position of the leaf, there being always two properly turned and properly spaced elbow slots for the reception of these inner movable posts. 95 The sheet may obviously be offset toward the bottom instead of toward the top, if desired.

I claim as my invention:

1. In a loose leaf binder, the combination 100 with a base member, of a pair of leaf-retaining posts fixed thereon and a pair of leaf-retaining posts movable thereon toward and from each other.

2. In a loose leaf binder, the combination 105 with a base member, of a pair of outer leaf-retaining posts fixed thereon and a pair of inner leaf-retaining posts arranged intermediate the units of the first mentioned pair and movably mounted on the base to move 110 toward and from each other.

3. In a loose leaf binder, the combination 115 with a base member, a pair of outer leaf-retaining posts fixed thereon and a pair of inner leaf-retaining posts arranged intermediate the units of the first mentioned pair and movably mounted on the base to move toward and from each other, of a leaf having inner and outer pairs of elbow slots to receive the posts, the units of each pair having their inner ends extending toward each other.

4. In a loose leaf binder, the combination 120 with a base member and a pair of relatively movable leaf-retaining posts mounted thereon, of a leaf having three or more elbow slots to receive the posts, and permit their movement, the said slots being equally spaced

to permit the posts to lock with different pairs of them and hold the leaf in different relatively offset positions.

5. In a loose leaf binder, the combination with a base member and a clamping member, of leaf-retaining posts mounted for relative movement on the base member and extending slidably through the clamping member, and means on the latter for actuating the posts.

10. 6. In a loose leaf binder, the combination with a base member and a clamping member, of leaf-retaining posts mounted for relative movement on the base member and extending slidably through the clamping member, 15 means on both the base and the clamping member for actuating the posts and a common operating device for both of said means.

7. In a loose leaf binder, the combination with a base member and a clamping member, 20 of leaf-retaining posts mounted for relative movement on the base member and extending slidably through the clamping member, means on both the base and the clamping member for actuating the posts and a common operating device for both of said means, 25 comprising a key extending through the clamping member and into the base member and upon which the former is slidable.

8. In a loose leaf binder, the combination 30 with a base member having leaf-retaining posts thereon and a clamping member slid- able on the posts toward and from the base member, of a clutch cooperating with one post to hold the clamping member against 35 leaves inserted between the members, a locking device cooperating with another post to prevent the members from moving toward each other and common actuating mechanism for releasing the clutch and for engaging the 40 locking device.

9. In a loose-leaf binder, the combination with a base member having fixed leaf-retaining posts thereon and also movable leaf-

retaining posts movable toward and from the fixed posts, and a clamping member slid- 45 able on the posts toward and from the base member, of a clutch cooperating with the fixed posts to hold the clamping member against leaves inserted between the members, locking devices cooperating with the movable posts to hold the members separated, and common actuating mechanism for the movable posts, for releasing the clutch and for engaging the locking device.

10. In a loose leaf binder, the combination with a base member having fixed leaf-retaining posts thereon and also movable leaf-retaining posts movable toward and from the fixed posts, and a clamping member slid- 50 able on the posts toward and from the base member, and having abutments thereon, of an automatic tilting clutch cooperating with the fixed posts to hold the clamping member against leaves inserted between the members, a sliding element on the clamping member 55 for actuating the movable posts and provided with cams for releasing the clutches and locking levers pivoted on the sliding element and actuated through contact with the abutments to cooperate with the movable 60 posts and hold the members separated.

11. A leaf blank for loose leaf binders having its binding edge provided with two pairs of elbow slots each adapted to admit a binding post against the side of which the 75 sheet is advanced edgewise, said slots being equi-distantly spaced from each other, and two adjoining slots of one pair extending in- 80 wardly from the edge of the leaf and thence toward the other pair which latter extend inwardly from the edge of the leaf and thence toward the first pair.

ERIC C. MOORE.
